(Continued)

Primary Examiner — T Chase Nelson

(57) **CLAIM**

The ornamental design for a shoe sole as shown and described.

DESCRIPTION

- 1.1: Perspective;
- 1.2: Front;
- 1.3: Back;
- 1.4: Right;
- 1.5: Left;
- 1.6: Top; and
- 1.7: Bottom

The broken lines show environmental structure in the form of a shoe upper as well as portions of the shoe sole that form no part of the claimed design.

1 Claim, 7 Drawing Sheets---
